UNITED STATES PATENT OFFICE.

GEORGE J. BIRNEY, OF TORONTO, ONTARIO, CANADA.

COLLAPSIBLE TOP FOR MOTOR-CARS.

1,278,837.

Specification of Letters Patent. Patented Sept. 17, 1918.

Application filed June 5, 1917. Serial No. 173,033.

To all whom it may concern:

Be it known that I, GEORGE JOHN BIRNEY, a subject of the King of Great Britain, and resident of the city of Toronto, county of 5 York, Province of Ontario, in the Dominion of Canada, have invented certain new and useful Improvements in Collapsible Tops for Motor-Cars, as described in the following specification and illustrated in the 10 accompanying drawings, that form part of the same.

The principal objects of the invention are, to eliminate the objectionable features of the present form of folding tops which are 15 formed of textile fabric and are quickly susceptible to wear and very soon become unsightly.

A further object is to dispense with the use of the unsightly appearing bows for 20 carrying the fabric tops, and to devise a form of top which may be formed of sheet metal of collapsible construction so as to be completely housed within a receptacle in the body of the car when the use of the top is 25 not desired.

A still further object is to devise a collapsible structure of top which will present a neat appearance and will be thoroughly 30 weatherproof.

The principal feature of the invention 35 consists in the novel construction and arrangement of a plurality of sections telescopically arranged and adapted to be telescoped together and to fit within a suitable pocket in the body of the car.

In the drawings, Figure 1 is a side elevational view of a motor car showing my improved top in its extended position.

Fig. 2 is an enlarged side elevational 40 view of the top shown partly telescoped and illustrating the manner of hinging the upper and back portions together.

Fig. 3 is an enlarged longitudinal sectional detail of the front section of the top 45 and a portion of the second section showing the method of inter-support and of weathering the joints.

Fig. 4 is a vertical sectional view through the rear portion of the car showing the 50 pocket for holding the collapsed top in a very much exaggerated form.

Fig. 5 is a transverse sectional view through the top showing the means of connecting the sections.

55 On reference to the accompanying drawings it will be seen that the top when raised

extends upwardly from the back portion of the body of the car and forwardly and presenting a very neat and effective appearance very similar to the new types of permanent 60 open sided tops, the bows being disposed with and the top rising directly from the body of the car and extending forwardly to the wind shield.

In order to accomplish this result I form 65 a pocket 1 in the rear of the body of the car which is open at the top. Arranged within this pocket are a plurality of telescopic metal sections, the section 2 being the lower back section which is adapted to 70 be raised and to form practically a continuation of the back of the car body, being held in the raised position by any suitable form of latch or locking device. The upper edge of the section 1 is preferably flanged 75 inwardly in a hook shape 3.

4 is the second back section which is slidably arranged within the section 2 and is adapted to rise above the same and to be locked by any suitable means in the ex- 80 tended positions. The main portion of this second section is adapted to slide past the hook edge 3 and the bottom edge of this second section is formed with a reverse flange 5 which is adapted to coöperate with the 85 turned edge 3 and to interlock therewith in a weather tight joint.

A suitable packing may be inserted in either of the joints or both of them to receive the abutting edge of the adjacent portion 90 to make the joint thoroughly weather tight against leakage or against the air.

An extension strip of metal 6 projects 95 backwardly from the flange 5 and fits in snug engagement with the inner side of the outer member but the inner member slides freely so as to move to the raised position to engage the outer edge of the lower member.

It will be seen that the lower member is 100 adapted to be raised to an extended position and the next succeeding member engages its upper flanged edge and this member has pivotally secured thereto a plurality of strips 7 formed with segmental shaped ends 105 8 which are mounted upon the pivot pins 9. Each of these members is provided with outer flanges 10 to engage the inner flanges of the adjacent members in locking contact.

The section 11 which forms the rear part 110 of the upper portion of the top is pivotally connected to the pivot pins 9 and flanged

corresponding to the other members to form a continuous closed casing when extended. The section 11 is adapted to rest in a horizontal position and extends forwardly and 5 carries the remaining sections 12 which are substantially duplicates thereof being supported the one within the other by grooved channel guides 13 secured to the inner side of the top portions of each section having 10 the longitudinal slots 14 through which the webs of T-shaped supports 15 extend. Each of these sections is provided at its rear end with a forwardly extending flange 16 corresponding with the flange 5 of the section 15 4 and each member is thus firmly supported laterally so that the whole structure will be perfectly rigid and secure when drawn to its extended position.

The forward member 17 is secured to the 20 top of the wind shield 18 in the usual manner and when it is desired to collapse the top the forward section is disconnected from the shield and slid backwardly into the next section. The next section is moved into the next 25 until the top sections are all telescoped. The rear top section is then swung upward on its pivot. The segmental shaped portions 8 fold the one within the other and when thus raised the upper back member 4 is dropped 30 into the lower member and the whole then drops into the pocket formed in the back of the car. A suitable cover may be placed over the receptacle for the top.

The setting of a top such as described is 35 extremely simple, it being only necessary to draw it out of its place, one section at a time until it is fully extended.

The device is very neat and adds much to the appearance of the car. It can be manufactured at extremely low cost as the parts 40 are all very simple and easily assembled.

A top such as herein described being of metal and of a very rigid construction lends itself to the adaptation of the conjoint use of 45 collapsible door panes and doors so that the car may be readily converted to being a closed car or an open car at will.

What I claim as my invention is:—

1. In a collapsible top for motor cars, the 50 combination with the car body having a pocket in the rear end, of a plurality of sections of rigid sheet material extending

across the car body and slidably arranged one within the other and forming the complete top and adapted to nest into said 55 pocket.

2. A collapsible top for motor cars, comprising a plurality of sections of rigid sheet material slidably arranged one within the other, to form the complete top, each section 60 having flanges adapted in the extended position to interlock and form a weather-tight joint.

3. A collapsible top for motor cars, comprising a back section formed of rigid sheet 65 material, and a top section formed of a plurality of members of rigid sheet material slidably arranged one within the other and pivotally supported from said back section, and forming the complete top. 70

4. A collapsible top for motor cars, comprising in combination with a pocket formed in the car body, a plurality of members of rigid sheet material slidably arranged one within the other and adapted to be extended 75 upwardly to form the back section, a plurality of members of rigid sheet material slidably arranged one within the other and pivotally connected to the back section and forming the roof section, and a plurality of 80 pivotal sections connecting the rear and top sections and forming the complete top.

5. A collapsible top for motor cars comprising a plurality of rigid sections of sheet material extending across the car and 85 formed to fit successively one within the other and each having flanges extending across the ends and interlocking with each other in the extended position, each section also having a rearward extension slidably 90 engaging the inner wall of the adjacent section to form a rigid support.

6. A collapsible top for motor cars, comprising a plurality of sections of rigid sheet material shaped to extend across the car 95 body and form the complete top and slidably arranged one within the other, longitudinally grooved guides arranged on the inner sides of each of said sections, and members arranged on each of said sections 100 slidably engaging the grooved guides of the adjacent section.

GEORGE J. BIRNEY.
